UNITED STATES PATENT OFFICE.

GREGORY CHMIELINSKI, OF CHICAGO, ILLINOIS.

FLYING-MACHINE.

1,276,032.

Specification of Letters Patent. Patented Aug. 20, 1918.

Application filed December 14, 1917. Serial No. 207,151.

To all whom it may concern:

Be it known that I, GREGORY CHMIELINSKI, a citizen of Poland, residing at Chicago, in the county of Cook and State of Illinois, have invented new and useful Improvements in Flying-Machines, of which the following is a specification.

This invention relates to flying machines of the heavier than air type, the broad object in view being to produce a flying machine of great passenger and freight carrying capacity and which may be also used in times of war for transporting troops, ammunitions of war, and also as a bomb dropping machine.

The invention relates more particularly to the frame structure and general arrangement of the fuselage or cabane and the aerial supporting and propelling means, whereby the machine may be handled with comparative ease and whereby increased lifting properties are imparted to the machine, rendering the same comparatively safe in operation, while, at the same time imparting an unusual degree of stability both in a fore and aft and lateral direction.

With the above and other objects in view the invention consists in the novel construction, combination and arrangement of parts, as herein described, illustrated and claimed.

In the accompanying drawings,

Figure 1 is a plan view of the improved flying machine.

Fig. 2 is a plan view partly in section of the frame of the fuselage or cabane.

Fig. 3 is a fragmentary perspective view of one of the end portions of the frame of the fuselage.

Fig. 4 is a fragmentary vertical section on an enlarged scale through one side of the fuselage.

Fig. 5 is a side elevation of the machine.

Fig. 6 is a vertical transverse section on the line *a—a* of Fig. 5.

Fig. 7 is a front elevation of the machine.

Fig. 8 is a perspective view of one of the propellers.

Fig. 9 is a bottom plan view of the same.

Referring primarily to Fig. 1, the machine in its general arrangement and structure comprises front and rear lifting or gliding surfaces 1 and 2, which are superimposed above a fore and aft elongated fuselage or cabane 3 having a substantially hemispherical bow or nose 4 and a corre-

spondingly shaped stern 5, imparting to the fuselage a stream-line formation which may be propelled through the air with a minimum head resistance.

60

Referring now to Figs. 2, 6 and 7, the fuselage comprises a series of circular bands or hoops 6 constituting transverse members of the frame. All of the hoops or circular frame members 6 which are in the form of endless rings, are connected at suitable intervals by means of longitudinal tie bars or stringers 7, thus forming a reticulated hollow cylindrical frame for the fuselage. At the top and bottom of the frame members 6, 70 there are other longitudinal frame members or stringers 8, 9, 10 and 11. The last named frame members are longer than the members 7 previously referred to and are also secured fixedly to the ring like frame members 6. 75 The members 8, 9, 10 and 11, however, extend beyond the front and rear members 6 where they are each bent into the form of a quarter circle. The member 11 has a bifurcated extremity 12 which straddles the adjacent extremity 9. The member 8 has a bifurcated end 13 which straddles the bifurcated end 12 of the member 11. The member 10 has a bifurcated end 14 which straddles the bifurcated end 13 of the member 8. 80 A single fastener 15, which may consist of a bolt, is inserted through the interfitting extremities of said members 8, 9, 10 and 11 as shown in Fig. 3, the extremities of all of said members being thus firmly secured together at the extreme bow and stern of the fuselage. A covering 16 of any suitable material, either metal or fabric is used as a sheathing for the fuselage frame. At the bow quadrant shaped glazed port holes or 85 windows 17 are provided for the use of the aviator as well as other occupants of the machine.

90

As indicated in Fig. 1, I employ four separate and independent motors 18 and 100 four separate and independent propellers 19. Each propeller is mounted upon an individual propeller shaft 20 having fast thereon a sprocket wheel 21 around which passes a chain 22 which extends around a 105 sprocket wheel 23 on the shaft of the respective motor 18. Each shaft 20 is journaled in bearings 24 at the lower extremities of an equal number of hangers 25, which are connected at their upper ends to fittings 26 110 on the under side of the adjacent supporting or gliding surface 1 or 2 as the case may be.

Braces or spreaders 27 extend from the fuselage laterally outward and having their outer extremities fastened to the bearings 24. Stays 28 have their outer extremities connected to the bearings 24 and the fittings 25 and have their inner extremities fastened to the fuselage frame. Other lower stays 29 extend from the bearings 24 inwardly and are fastened to the fuselage frame. The 10 bearings 24 for the propeller shafts 20 are thus securely braced in relation to the fuselage. It will now be observed that by varying the rate of speed of the several motors, the corresponding change in the ratio of 15 speed of the propellers may be obtained to assist in steering and banking operations and also for restoring and maintaining lateral and longitudinal stability. The aviator's seat 30 is arranged centrally of the 20 fuselage as shown in Fig. 6, and adjacent to the controls designated generally at 31. By reason of the construction hereinabove outlined a single companionway 32 is formed leading the entire length of the fuselage as 25 indicated in Figs. 1 and 6 and passenger stays 33 may be arranged at opposite sides of said companionway or single aisle.

Each of the propellers is preferably formed of a substantially rectangular plate 34 of light metal such as aluminum or aluminum alloy. On the under side of the plate 34 cleats 36 arranged substantially parallel and in spaced relation to each other are fastened to said sheet by means of rivets 35 or the equivalent thereof. About centrally of their length, the cleats 36 are formed with eyes 37 through which the respective propeller shaft 20 is inserted and fastened. By reference to Figs. 7 and 8, it will be observed 40 that the end portions of the propeller are pitched or inclined at a suitable angle to propel the machine ahead and at the same time, act as lifting propellers. Each of the supporting or gliding surfaces 1 and 2 has 45 its end or wing portions upwardly inclined at a dihedral angle as indicated in Figs. 6 and 7, while the extreme end portions thereof are slightly recurved in compound formation as shown in the same figures, giving a 50 bird-like contour to said supporting and gliding surfaces.

In conjunction with each of the motors 18, I employ two fuel tanks 38 and 39. Said tanks are arranged in the front and rear 55 portions of the fuselage and leading from each pair of tanks to the respective motor 18 are one or more fuel feed pipes 40. At the stern of the fuselage, I arrange a rudder bracket 41 having a semi-circular base portion which is terminally fastened to the fuselage at the points 42. At the rear end, said bracket 41 is of cruciform formation, embodying two upwardly and rearwardly extending arms 43 and two horizontally and 60 rearwardly extending arms 44. A centrally

pivoted or bifurcated horizontal rudder 45 is mounted upon an operating rock shaft 46 journaled in the horizontal arms 44 of the rudder bracket, and a vertical rudder 47 is fast to an operating rock shaft 48 journaled 70 in the horizontal arms 43 of said rudder bracket. Suitable rudder operating connections extend from said rock shafts inboard where they are connected to one of the controls 31 hereinabove referred to. 75

The landing gear comprises an axle 49 extending transversely under the fuselage and having mounted thereon supporting wheels 50. The axle 49 is carried by the lower extremities of vertical plunger rods 80 51 which are slidable through openings in a bottom bracket 52 fastened to the bottom of the fuselage frame as shown, for example, in Fig. 6. Encircling each of the plunger rods 51 is a coil compression spring 53 which acts 85 as a shock absorber and cushions the load of the machine in relation to the axle 49. It will be seen from Fig. 5 that front and rear axles 49 are provided for the proper support of the machine on the ground. Flexible 90 stays 54 may be interposed between each axle 49 and the bottom frame 52 or the frame of the fuselage as may be preferred.

The construction hereinabove described provides for a light weight, thoroughly 95 braced fuselage and wing structure, the fuselage having a large carrying capacity for passengers or freight. By employing the front and rear supporting or gliding surfaces, the longitudinal stability of the machine is greatly increased as compared with the present date type of aeroplane which has the supporting and gliding surface or surfaces arranged adjacent to the head or bow of the fuselage. Both the lateral and longitudinal stability of the machine are also increased by the employment of the propellers under the arrangement described and shown. Ample clearance for said propellers is provided at opposite sides of the fuselage and 105 beneath the supporting and gliding surface. The bearings for the propeller shafts and the outriggers or hangers therefor, are thoroughly braced so as to prevent undue or excessive vibration of the propeller shafts 110 under the rapid rotation of the propellers. The controls generally shown at 31 will embody a plurality of small levers 55 by means of which the engines 18 may be throttled in order to vary the ratio of speed of the several propellers for the purpose of restoring 115 the equilibrium of the machine or properly banking the same in making a turn. This will also be found a very desirable feature in case of injury to either the horizontal or 120 vertical rudder or the controls thereof. This adds greatly to the safety of the machine. 125

I claim:

1. In a flying machine, a fuselage frame comprising a fore and aft series of circular 130

- hoops, longitudinal frame bars to which all of said hoops are fastened, and other longitudinal frame bars to which said hoops are fastened, the last named frame bars extending beyond the front and rear hoops and having front end portions curved inwardly and fastened at their extremities to provide hemispherical bow and stern portions for said fuselage frame.
- 10 2. In a flying machine, a fuselage frame comprising a fore and aft series of circular hoops, longitudinal frame bars to which all of said hoops are fastened, and other longitudinal frame bars to which said hoops are fastened, the last named frame bars extending beyond the front and rear hoops and having front end portions curved inwardly and fastened at their extremities to provide hemispherical bow and stern portions for said fuselage frame, propeller shafts extending parallel to the longitudinal
- axis of the fuselage frame, and supporting outriggers for said shafts fastened to the fuselage frame.
3. In a flying machine, a fuselage frame 25 comprising a fore and aft series of circular hoops, longitudinal frame bars to which all of said hoops are fastened, other longitudinal frame bars to which said hoops are fastened, the last named frame bars extending 30 beyond the front and rear hoops and having front end portions curved inwardly and fastened at their extremities to provide hemispherical bow and stern portions for said fuselage frame, the said curved end portions of the last named longitudinal frame bars being overlapped in bifurcated formation, and a single fastener inserted through 35 said overlapping extremities.

In testimony whereof I affix my signature. 40

GREGORY CHMIELINSKI.
